United States Patent Office.

DAVID EYNON, OF RICHMOND, VIRGINIA, ASSIGNEE TO THE TREDEGAR COMPANY, OF SAME PLACE.

Letters Patent No. 69,085, dated September 24, 1867.

IMPROVEMENT IN ROLLING APPARATUS FOR ROLLING CHAIRS FOR RAILROADS.

The Schedule referred to in these Letters Patent and making part of the same.

TO ALL WHOM IT MAY CONCERN:

Be it known that I, DAVID EYNON, of Richmond, in the county of Henrico, and State of Virginia, have invented a new and useful Improvement in Rolls for Making Railroad Chairs, of which the following is a full, clear, and exact description, reference being had to the accompanying drawings, which make part of this specification, and in which—

Figure 1 shows a view in elevation of my improved rolls, and

Figure 2 a vertical transverse section through the same, at the line *xx* of fig. 1.

It is the object of my invention to roll a railroad chair from a rectangular pile without the necessity of bending down the lips of the chair, which are liable to crack when so bent; and to this end my invention consists in passing the pile between rolls containing a series of grooves of the proper form to give the desired shape to the chair, as hereinafter described. My invention further consists in placing a pair of flattening-rollers in rear of one of the grooves, as hereinafter described.

To carry out my invention I mount a pair of rolls, A B, in proper bearings, and drive them in any suitable well-known way. A series of matched grooves is formed in these rolls, so as to leave openings of the forms shown at 1, 2, 3, 4, 5, 6, 7, which are counterparts of the form given to the chair in the successive stages of its manufacture. In making the chairs a heated pile is passed through each groove successively, beginning with No. 1 and continuing to No. 7. By reference to the drawings it will be seen that after passing through groove No. 4 the bar has assumed a concavo-convex shape, with the concavity beneath. To flatten out the bar properly I arrange a pair of rollers, C D, in rear of the fifth groove, and pass the bar between them before it enters the sixth groove. This flattens it properly, and it is then finished by passing it through Nos. 6 and 7. The bar is then sawed into proper lengths, and the chair is complete with the exception of the holes for the insertion of the spikes.

What I claim as my invention, and desire to secure by Letters Patent, is—

The rolls, grooved as described and shown in the drawings.

I also claim the flattening-rollers, arranged in rear of the fifth groove, as described, for the purpose set forth.

DAVID EYNON.
